UNITED STATES PATENT OFFICE.

EDWARD BATTEN, OF BECKENHAM, ENGLAND, ASSIGNOR OF ONE-FOURTH TO ROWLAND WILLIAM THOMAS VAILE, OF BECKENHAM, ENGLAND, ONE-FOURTH TO ARTHUR BARBER, OF BROMLEY, ENGLAND, AND ONE-FOURTH TO BECKENHAM MOTOR COMPANY, LIMITED, OF BECKENHAM, ENGLAND.

PUMP.

1,370,181.

Specification of Letters Patent.

Patented Mar. 1, 1921.

Application filed September 6, 1919. Serial No. 322,179.

To all whom it may concern:

Be it known that I, EDWARD BATTEN, a subject of the King of Great Britain, residing at 17 Westfield road, Beckenham, in the county of Kent, England, have invented certain new and useful Improvements in or Relating to Pumps, of which the following is a specification.

This invention relates to pumps of the kind operated by the foot and intended especially for inflating pneumatic tires.

According to the invention, the reciprocating member or piston of the pump is connected through pivoted toggle like links to a longitudinal member constituting the base plate of the pump and also to the operating pedal which latter is connected by another longitudinal member to the upper part of the pump barrel remote from the pedal. The said toggle like links are preferably disposed in two pairs in such a manner that the plane containing the pivotal axis of the pair at the base plate and the pivotal axis of the pair at the pedal, when the latter is in its uppermost position, intersects a continuation of the axis of the pump barrel at a point considerably farther from the piston, than the axis of the pivotal connection by which the two pairs of links are joined to said piston. In other words the two longitudinal members are disposed at an angle to each other and when two pairs of links are employed as aforesaid each of the longitudinal members may also be arranged in pairs. The barrel is adapted to oscillate about a trunnion at the rear end of the base plate. In order to produce a symmetrical construction, the links of each pair may be of the same length and the axis of the said trunnion is situated at a distance equal to the length of each of the said tension members from the axis at which the lower pair of links are pivoted to the base plate. We provide resilient means which may be in the form of a compression spring situated around the piston rod with one end abutting against a member on the pump barrel and the other end against a member on the piston rod. These resilient means operate on the toggle-like links in a direction to keep the longitudinal members apart and put them in a condition of tension.

In order that the said invention may be clearly understood and readily carried into effect, the same will now be more fully described with reference to the accompanying drawings in which:—

Figure 1 is a vertical section of one form of the improved air pump with the pedal in its uppermost position.

Fig. 2 is an elevation of the same with the pedal depressed, and

Fig. 3 is a plan of Fig. 2.

1 is the oscillatory barrel or cylinder of the pump. 2 is the rod of the piston 3. 4, 5 are the two pivoted links connecting the piston rod 2 to the lower longitudinal members constituting the base plate 6 of the pump, while 7, 8 are the two pivoted links connecting the said piston rod to the operating pedal 9. 10, 11 are the upper longitudinal members consisting of steel straps for connecting the pedal 9 to the upper rear part of the barrel 1 and 12 is the spring for exerting tension on the longitudinal members 7 and for returning the piston 3 when the pressure of the user's foot on the pedal is relieved.

The pump barrel is pivoted at its lower rear portion by means of trunnions 13 to two upstanding lugs 14, 15 at the rear end of the base plate 6. At its forward end the base plate has two further upstanding lugs 16, 17 through which extends a pin 18 which serves as a pivot for the lower ends of the links 4, 5 and is secured in place by means of transverse pins passing through the lugs, a sleeve or distance piece being provided around the said pin 18 and serving to keep the lower ends of the said links 4, 5 at their proper distance apart. The upper ends of these links 4, 5 are pivoted by means of a long pin 21 to the lower ends of the links 7, 8 and also to a member 20 which is screw threaded into the piston rod 2 which is tubular, the said pivot pin 21 being fixed to the member 20 by a tapered pin 22. This long pivot pin is provided with four spacing washers 23, 24, 25, 26 and outside the washers 23 and 26 split pins pass through the said pivot pin. At their upper ends the links 7, 8 engage a pivot pin 27 fixed by a tapered pin 29 to a lug 28 projecting downward from the pedal 9.

The upper longitudinal members or steel straps 10, 11 connect the pedal 9 to two ears 30, 31 on the pump barrel 1, and are about the same length as the base plate 6. The 5 four links 4, 5, 7, 8 are all equal in length so that they are equally inclined to the axis of the piston rod 2 and during the downward movement of the pedal 9 the pivot pin 21 remains equidistant from the base plate 10 6 and the straps 10, 11.

The rear of the pump barrel 1 is closed by an aluminium casting 34 which is flat on its inner face. The delivery passage of the 15 pump is formed in the casting 34 and is furnished with a ball non-return valve 35 and with a pressure gage 36 and flexible tubular connection 37 as usual.

The piston 3 is also an aluminium casting somewhat of mushroom shape. Its stem is 20 screw threaded and enters the tubular piston rod 2. A disk 38 is threaded upon the stem of the piston and a cup leather 39 is clamped between the disk 38 and the piston 3. The pump barrel has a perforated cover 41 inserted in its open end and retained therein by screws 42. The spring 12, made for the sake of compactness, as a volute steel spring is disposed between the perforated cover 41 and a washer 43, which is held in place 25 against the end of the tubular piston rod 2 by a lock nut 44. A relatively weak cushioning spring 45 is inserted between the disk 38 and the cover 41. The rear face of the piston is flat and means are provided for adjusting the stroke of the pump so that the rear face of the piston at the end of the delivery stroke just comes into contact with the front face of the casting 34 with the result that the only clearance the pump has 30 is the volume of the small delivery passage 40 in the casting 34. The means for effecting this adjustment comprise the threaded stem of the member 20 which can be adjusted within the tubular rod 2 until when 35 the pedal 9 is fully depressed the piston 3 just comes into contact with the casting 34, the parts being locked in the adjusted position by the nut 44.

In operating the pump, the pedal 9 is depressed by the foot of the user into the position shown in Figs. 2 and 3, thereby causing the piston to perform the delivery stroke and force the air contained in the barrel through the delivery passage 40 beyond the 50 ball valve 35. On the return or suction stroke which occurs when the pressure of the user's foot on the pedal is relieved the valve 35 closes and air is drawn in through the perforated cover 41 past the cup-leather 39. 55 During the operation of the pump the barrel 1 oscillates about the trunnion 13, so that the pin 21 always keeps in line with the axis of the barrel and in the downward movement the spring 12 is compressed and the 60 upper longitudinal members or straps 10, 11

are also slightly bent thus assisting the action of the spring 12 to some extent during the return movement.

In order to enable the pump to be packed into a small space during transport the pedal 70 9 is cast with a projecting hook 46 and the front of the base plate has a wire loop or stirrup 47 which is capable of engaging with the hook 46 to hold the pump in the depressed position. The pump is shown in this 75 position in Fig. 2. By depressing the pedal 9 beyond the position indicated by Fig. 2 until the hook 46 disengages the loop 47 the latter will become released by the action of gravity. 80

I claim:

1. In a foot operated pump, the combination of a base plate, a cylinder pivotally mounted on said base plate, a piston in said cylinder, an operating pedal, a connection between said pedal and said cylinder and toggle links connecting said pedal and base plate and coupled to said piston. 85

2. In a foot operated pump, the combination of a base plate, a cylinder pivotally mounted on said base plate, a piston in said cylinder, an operating pedal, a connection between said pedal and said cylinder, toggle links connecting said pedal and base plate and coupled to said piston, and means 90 for normally straightening said toggle and elevating said pedal. 95

3. In a foot operated pump, the combination of a base plate, a cylinder pivotally mounted on said base plate, a piston in 100 said cylinder, an operating pedal, a connection between said pedal and said cylinder, toggle links connecting said pedal and base plate and coupled to said piston, and a spring interposed between said cylinder and 105 said toggles tending to straighten said toggle and elevate said pedal.

4. In a foot operated pump, the combination of a base plate, a cylinder pivotally mounted on said base plate, a piston in said cylinder, an operating pedal, a resilient connection between said pedal and said cylinder, toggle links connecting said pedal and base plate and coupled to said piston, and a spring interposed between said cylinder and 110 said toggles tending to straighten said toggle and elevate said pedal. 115

5. A foot-operated pump comprising a stationary base plate, a cylinder connected thereto in an oscillatory manner, an operating pedal, a pair of tension members coupling said pedal to said cylinder, a piston adapted to reciprocate within said cylinder and two pairs of pivoted links connecting said piston respectively to said pedal and 120 to one end of said base plate. 125

6. A foot-operated pump comprising a stationary base plate, a trunnion mounted on the rear end thereof, a cylinder formed with rearwardly-disposed upward projec- 130

tions and mounted in an oscillatory manner in said trunnion, a piston adapted to reciprocate within said cylinder, a pair of pivoted links connecting said piston to the 5 forward end of said base plate, an operating pedal, a further pair of pivoted links substantially equal in length to the pair of links aforesaid and connecting said piston to said pedal, and a pair of tension members connecting said pedal to said upward 10 projections and substantially equal in length to the distance between said trunnion and the point of connection of said links with the forward end of said base plate.

15 7. A foot pump consisting in the combination of an oscillatory pump cylinder and piston, relatively movable longitudinal members inclined at an angle to each other and between which said oscillatory cylinder 20 and piston are situated, toggle-like links connecting the outer ends of said longitudinal members to the piston, resilient means for exerting pressure on the toggle-like links in a direction to separate said longitudinal 25 members and put them in a condition of tension along their length and means for enabling the user to exert pressure on the upper end of the toggle-like links against the pressure of said resilient means and 30 thereby cause the longitudinal members to approach each other thus folding the links and operating the pump piston.

8. A foot pump consisting in the combination of an oscillatory pump cylinder and piston, relatively movable longitudinal tension members inclined at an angle to each other and between which said oscillatory cylinder and piston are situated, toggle-like links connecting together the outer ends of 35 said longitudinal tension members, a rod on said piston connected to the intermediate joint of the toggle-like links, a spring surrounding the piston rod and abutting at one end against the cylinder and at the other 40 end against a shoulder on the piston rod to separate said longitudinal members and put them in their condition of tension along their length and means for enabling the user to exert pressure on the upper end of the 45 toggle-like links for actuating the latter against the pressure of said spring.

9. A foot pump consisting in the combination of an oscillatory pump cylinder and piston, relatively movable longitudinal tension members inclined at an angle to each other and between which said oscillatory cylinder and piston are situated, toggle-like links connecting together the outer ends of 50 said longitudinal members, a rod on said piston connected to the intermediate joint of the toggle-like links, a spring surrounding the piston rod and abutting at one end against the cylinder and at the other end against a shoulder on the piston rod to separate 55 said longitudinal members and put them in their condition of tension along their length and means for enabling the user to exert pressure on the upper end of the toggle-like links for actuating the latter against the pressure of said spring.

them in their condition of tension along their length and an operating pedal at the upper end of the toggle-like links.

10. A foot pump consisting in the combination of an oscillatory pump cylinder and piston, relatively movable longitudinal tension members inclined at an angle to each other and between which said oscillatory cylinder and piston are situated, the lower longitudinal member constituting a base 70 plate, means for pivotally connecting said cylinder to the rear end of said base plate, toggle-like links connecting together the outer ends of said longitudinal members, a rod on said piston connected to the intermediate joint of the toggle-like links a spring surrounding the piston rod and abutting at one end against the cylinder and at the other end against a shoulder on the piston rod to 75 separate said longitudinal members and put them in their condition of tension along their length and an operating pedal at the upper end of the toggle-like links.

11. A foot pump consisting in the combination of an oscillatory pump cylinder and piston, relatively movable longitudinal tension members arranged in pairs and inclined at an angle to each other and between which said oscillatory cylinder and piston are situated, the lower pair of said 90 members constituting a base plate, trunnions on said cylinder pivotally mounted in lugs at the rear end of said base plate, two pairs of toggle-like links connecting together the outer ends of said longitudinal 95 members, a rod on said piston connected to the intermediate joint of the toggle-like links, a spring surrounding the piston rod and abutting at one end against the cylinder and at the other end against a shoulder on the piston rod to 100 separate said longitudinal members and put them in their condition of tension along their length and an operating pedal at the upper end of the 105 toggle-like links.

12. A foot pump consisting in the combination of an oscillatory pump cylinder and piston, relatively movable longitudinal tension members inclined at an angle to each other and between which said oscillatory cylinder and piston are situated, the lower longitudinal member constituting a base 110 plate, trunnions on said cylinder pivotally mounted in lugs at the rear end of said base plate, means connecting the inner end of the upper tension member to the rear end of 115 said cylinder, toggle-like links connecting together the outer ends of said longitudinal members, a rod on said piston connected to the intermediate joint of the toggle-like 120 links, a spring surrounding the piston rod and abutting at one end against the cylinder and at the other end against a shoulder on the piston rod to separate said longitudinal members and put them in their condition of 125 130

tension along their length and an operating pedal at the upper end of the toggle-like links.

13. A foot pump consisting in the combination of an oscillatory pump cylinder and piston, relatively movable longitudinal tension members inclined at an angle to each other and between which said oscillatory cylinder and piston are situated with the point of oscillation between the inner ends of said longitudinal members, toggle-like links connecting together the outer ends of said longitudinal members, a rod on said piston connected to the intermediate joint

of the toggle-like links, a volute spring surrounding the piston rod and abutting at one end against the cylinder and at the other end against a shoulder on the piston rod to separate said longitudinal members and put them in their condition of tension along their length and means for enabling the user to exert pressure on the upper end of the toggle-like links against the pressure of said volute spring and thereby cause the longitudinal members to approach each other thus folding the links and operating the pump piston. 15 20 25

EDWARD BATTEN.
